HOT GAS OUTLET THIMBLE

Richard C. Wright, Bay Village, Ohio, assignor to
Iron Fireman Manufacturing Company, Port-
land, Oreg.

Application April 8, 1944, Serial No. 530,219

3 Claims. (Cl. 110—49)

This invention relates generally to burners or furnaces, and particularly to a hot gas outlet thimble to be used in conjunction therewith.

The main object of this invention is to provide a suitable connection for withdrawing hot furnace gases through a refractory wall from a furnace in which fuel is being burned.

The second object is to provide suitable means for supporting the end of a conduit within which the gases are conveyed from the furnace.

The third object is to prevent excessive overheating of the end of the conduit, and to provide an expansion joint therefor.

The fourth object is to provide means for regulating the temperature of the gases in the conduit by diluting them with air from the surrounding atmosphere.

These and other objects will become more apparent from the specification following as illustrated in the accompanying drawings, in which:

Fig. 1 is a fragmentary view of a representative form of furnace installation showing a boiler setting broken away in section.

Fig. 2 is a plan of the device with parts broken away in section.

Fig. 3 is a front elevation of the device with parts broken away.

Referring in detail to the drawings, there is shown a furnace front 10, grates 11, tubes 12, and fire door 13 of a conventional type of installation. There is also indicated the fuel delivery pipe 14 through which solid fuel is conveyed pneumatically and discharged through the tip 15 extending through the opening 16 of the wall 10. Above the opening 16 is disposed the opening 17 which extends through the wall 10 to receive the hot gas thimble, which I am about to describe.

Referring more particularly to my invention, same will be seen to consist of a cylindrical thimble 18 having a flanged rim 19 from which project the ears 20 with holes 21 for anchor bolts not shown, which are anchored in the wall 10. It is preferable to provide ribs 23 behind the ears 20 for the purpose of stiffening the ears and also to resist rotation of the sleeve 18 within the opening 17.

Extending inwardly from the flange 19 are the projections 24 whose sides 25 are radial and whose edges 26 are arcs of a circle concentric with the thimble 18. Longitudinal ribs 27 and 28 reinforce the projections 24 and the edge 29 of the rib 27 projects slightly beyond the arcuate edge 26. The ribs 28 may be somewhat lighter than the ribs 27 and need not project beyond

the arcuate surfaces 26 of their respective projections 24, the purpose of this construction being to hold the hot gas pipe 30 concentric with relation to the thimble 18 and yet hold it out of engagement with the edge 26 upon which it would ordinarily rest.

Referring now to the movable member of the device, same will be seen to consist of a valve plate 30—A having a central opening 31 which extends generally to the inner edge 32 which conforms with the interior of the thimble 18. The edge 32 has extending therefrom the inturned projections 33 which are sufficient to bridge the gaps between the radial sides 25 of the projections 24. The inner edges 34 of the projections 33 are formed on the same radii as are the inner edges 26 of the projections 24. Formed in the periphery of the plate 30 are a plurality of arcuate slots 35 adapted to freely receive the bolts 36 which are threaded into the tapped openings 37 in the flange 19.

It can be seen from the foregoing that with this construction, the hot gas pipe 30 is held along the axis of the opening 17 by means of the supporting projections 21 and 28 which are cooled by the air drawn in through the openings. It will also be seen that by means of this construction the temperature of the gases passing through the pipe 30 may be easily controlled as well as the proportion of air and partially or fully burned gas, by merely rotating the plate 30—A at the same time affording an expansion joint, a pipe support and a cold air mixing thimble all in two simple castings, and also provides a way of admitting the cold air to the intake end of the hot gas pipe so as to cool its entire length, in addition to rendering it unnecessary to accurately cut the hot gas pipe for length when installing same.

When installing this thimble, the opening 17 should be located as high as possible in the front boiler wall 10 and as close to the center as practical.

The thimble should be installed in the furnace wall in such a position that it will act as an expansion joint and the end of the hot gas pipe 30 should not extend into the casting 18 more than three inches.

It is desirable to provide a ring of plastic refractory material 38 around the inlet 17 to shield the pipe 30 and the thimble casting 18 from the direct, radiant heat of the furnace. The lower part 39 of the ring 38 should be sloped as indicated in Fig. 1 to permit entrance of a cleaning

tool to remove any accumulation of slag that may form over the opening.

When installing this thimble, care should be taken that the heavier supporting web 27 is located at the bottom, that is, the underside of the pipe 30. Care should be taken to see that the pipe 30 rests freely upon the edge 29 of the web 27, and that there is sufficient clearance for expansion when the pipe 30 is heated.

A slag drip 40 should be provided by allowing one course of the fire brick above the intake opening 17 to project about two inches into the furnace, thereby preventing the slag from accumulating around the opening 17.

While I have thus illustrated and described my invention, it must be understood that I do not wish to be limited to the precise details shown herein, but I intend to cover all such forms and modifications therein as fall fairly within the appended claims.

I claim:

1. A device of the class described, consisting of a cylindrical thimble, a flange extending inwardly and outwardly from said thimble the inwardly extending portion of said flange being cut away at spaced intervals, a circular disc having a circular opening formed therein substantially equal to the opening in said flange, said disc having spaced cut-out portions in said flange when said disc is loaded with relation thereto, said thimble having radial ribs on the interior thereof, the lowermost one of which extends above the lowermost interior edge of said disc, and means for fixing the relationship between said disc with relation to said flange.

2. In a device of the class described, the combination of a cylindrical thimble having a flange at one end thereof extending outside of and inside of said thimble normal to the axis of the

thimble, a hot gas pipe extending axially through said thimble and flange, radial ribs within said thimble extending to the interior of said flange, the lowermost rib constituting a support for said gas pipe, the innermost portion of said flange having cut-away portions spaced from each other and extending from the exterior of the gas pipe to the interior of said thimble, a disc rotatably mounted against said flange having a central opening substantially the same as that of said flange, and bolts extending through said disc and flange whereby the relative relation of said disc and flange may be fixed.

3. In a fluid conveying system, the combination of a refractory wall constituting a boiler front and having an opening therethrough together with a cylindrical thimble mounted in said opening and having a flange on the outer end thereof extending outwardly and inwardly from said thimble in a plane normal to its axis, a disc constituting a closure for said thimble having means for revolvably mounting same thereon and securing its position with relation thereto, a hot gas pipe extending through said disc and inner flange portion extending part way into said thimble, the portions of said disc and flange immediately surrounding said gas pipe having cut-out portions adapted to register when said disc is turned to a given position, said thimble having radial internal ribs extending to the internal edges of said disc and innermost flange portions, the lowermost rib constituting a support for said hot gas pipe, the end of said boiler front opening nearest the combustion chamber having a restricted inlet communicating with said hot gas inlet, said furnace front having a slag drip formed above said restricted opening spaced from the interior face of the furnace front.

RICHARD C. WRIGHT.
